UNITED STATES PATENT OFFICE.

GERTRUDE M. GOEBEL, OF CANTON, OHIO, ASSIGNOR TO JOHN L. HOWENSTINE, OF MASSILLON, OHIO.

BLOOMERS.

Application filed August 7, 1922. Serial No. 580,204.

To all whom it may concern:

Be it known that I, GERTRUDE M. GOEBEL, a citizen of the United States, residing at Canton, in the county of Stark and State of Ohio, have invented a certain new and useful Improvement in Bloomers, of which the following is a specification.

This invention relates to an undergarment for women and more particularly to a bloomer garment and has for its objects to provide a garment of this character formed of material such as muslin, nainsook, crêpe, sateen or other material suitable for the purpose.

15 Other objects of the invention are to provide a garment of this character formed from a minimum number of pieces of material and so designed as to provide for a fullness in the back portion of the garment, 20 without requiring the use of gathers or plaits along the side seams thereof.

The above and other objects may be attained by constructing the garment as illustrated in the accompanying drawing, in 25 which—

Figure 1 is a perspective view of a figure wearing a garment embodying the invention, showing the front of the same;

Fig. 2, a similar view showing the back 30 of the garment;

Fig. 3, a view of the pattern of one-half of the front of the garment; and

Fig. 4, a pattern of the back piece of the garment.

35 Similar numerals refer to similar parts throughout the drawing.

The front of the garment is formed of two similar sections as illustrated at 1 in Fig. 3, each section comprising the reduced 40 upper body portion 2 and the widened lower leg portion 3, the outer side edge of each portion 1 being substantially straight as shown at 4, the upper edge 5 being tapered down toward the center 6. The inner side edge 7 of the body portion is concaved as at 8 terminating at the point 9, the inner side edge of the leg portion being straight as shown at 10.

45 The back indicated generally at 11, is preferably formed of a single piece as shown in Fig. 4, although if desired, the back may be made in halves connected at the center as indicated by the dotted line 12. This back member has the top edge 13 inclined 50 upward from both sides toward the center

14, the side edges 15 being of substantially the same length as the side edges 4 of the front member and being provided with the convex upper portions 16 to provide a fullness in the back of the garment and over 60 the hips of the wearer. The curved lower edge 17 upon the back member produces the back leg portions 18.

In assembling the garment, the two front sections are placed together and stitched along the edge 7 between the points 6 and 9. One side edge 4 of the front is stitched to each side edge 15 of the back and these edges being of the same length, a smooth seam is formed at each side of the garment, 70 as indicated at 4—15 in Figs. 1 and 2, no gathers, plaits or the like being necessary to produce a fullness in the back portion of the garment.

The point 9 of the front is placed at the 75 point 19 of the back and the side edges 10 of the front leg portions are sewed to the curved edge 17 of the back leg portions, as indicated at 10—17 in Figs. 1 and 2, thus forming the leg openings from the lower 80 edges 20 and 21 respectively of the front and back leg portions. The curved edge 17 of the back piece is shown as of greater length than the combined length of the two edges 10 of the two front pieces when sewed together, thus providing a fullness in the back along the seam 10—17 when the front and back members are sewed together. These leg openings are preferably gathered together by an elastic band as indicated at 85 90 22 in Figs. 1 and 2 and an elastic band is also preferably located around the waist of the garment as indicated at 23.

The garment thus produced has a straight 95 front and substantial fullness in the back portion and over the hips of the wearer, making the garment comfortable and permitting the wearer to bend or turn in any direction, without causing the garment to bind at any point and without danger of 100 ripping or tearing the same.

It will be seen that by providing the upper inclined edges 5 and 13 upon the front and back portions respectively of the garment, the center of the waistline at the back 105 will be considerably higher than the center of the waistline at the front and the points 14 and 19 in the back being spaced considerably further apart than the points 6 and 9 in the front, a substantial fullness will 110

be provided in the seat portion of the garment, while the outwardly curved edges 16 of the back provide for a fullness over the hips of the wearer.

5 I claim:—

A bifurcated garment including a back member, the side edges of which are slightly concaved below the center and convexed above the center to provide a fullness over 10 the hips, the upper edge being inclined downward toward both side edges from the

center, the lower edge being concaved in an arcuate line, and a front member having straight side edges equal in length to the side edges of the back member and having 15 inner straight edges of a combined length considerably less than the arcuate lower edge of the back member and arranged to be attached thereto to provide fullness in the seat portion of the garment by plaiting 20 the remaining portion of the arcuate edge.

GERTRUDE M. GOEBEL.
